UNITED STATES PATENT OFFICE.

JOHN THAISON, OF RIOGRANDE, TEXAS; MRS. JOHN THAISON ADMINISTRATRIX OF
SAID JOHN THAISON, DECEASED.

FILM-SPlicer.

1,198,163.

Specification of Letters Patent. Patented Sept. 12, 1916.

Application filed January 10, 1916. Serial No. 71,280.

To all whom it may concern:

Be it known that I, JOHN THAISON, a citizen of the United States, residing at Rio-grande city, in the county of Starr, State 5 of Texas, have invented certain new and useful Improvements in Film-Splicers; and I do hereby declare the following to be a full, clear, and exact description of the invention, such as will enable others skilled in the art 10 to which it appertains to make and use the same.

This invention relates to film splicers, and may be particularly associated with means for connecting the broken ends of moving 15 picture film or strip.

As is well known to those familiar with moving picture projecting machinery, the film employed in connection with the apparatus often becomes broken, which necessitates immediate connection of the broken 20 ends. To temporarily cement the broken ends of the film to continue the operation of the machine, the broken ends must be overlapped a considerable distance to effect a 25 positive connection, which obliterates a part of the picture and causes a jumping or lack of smoothness of the picture when projected afterwards. Another disadvantage to this 30 practice is that the time consumed in effecting the connection causes inconvenience to the machine operator, as well as annoyance to the audience. Again, by this method, it is necessary before the display film is 35 rewound to further exhibit same, that the cemented ends must be disconnected, realined, and properly and permanently cemented to prevent misframing of the film in subsequent 40 exhibitions. Other methods for the attainment of the desired ends have been rejected, but all have proven inadequate or impractical.

It is the primary object of my invention to overcome the objections common to such methods, and to provide a simple, inexpensive, and thoroughly efficient means for temporarily connecting the broken ends of picture strip without loss of time or inconvenience to the operator, and without reducing the length of the film.

50 A further object of the invention is to provide a device for the purposes described, by the use of which the machine operator during the rewinding function may at once determine the exact location of the broken 55 section necessary to be permanently con-

nected to repair the same permanently for further exhibition.

With these objects in view, together with others which will appear as the description proceeds, the invention resides in the novel 60 combination and arrangement of parts, all as will be described more fully hereinafter, illustrated in the accompanying drawings, and particularly pointed out in the claims.

The invention will be best understood by 65 reference to the accompanying drawings, wherein:

Figure 1, is a fragmentary side elevation of a conventional form of moving picture projecting apparatus, illustrating diagrammatically the application of a device constructed in accordance with my invention, to the film used in connection therewith. Fig. 2, is an enlarged plan view of the plate constituting my splicer, and a fragmentary 75 end of film, and Fig. 3, is an enlarged section taken substantially upon line 3—3 of Fig. 2, and illustrating the splicer as applied to a film.

Referring more particularly to the drawings, 5 and 6 indicate respectively the broken ends of a conventional form of picture strip or film, the said film being provided as is usual adjacent its lateral edges with feed openings 7 whereby the film may 85 be properly fed to and through the projecting apparatus.

In the attainment of the desired ends, I employ a plate 8 of thin metal of such nature as to be capable of flexion, the said plate 90 being adapted to be interposed between to connect the said broken film ends. This plate is of relatively short duration, and is in width equal to that of the picture strip. To facilitate the ready connection of the 95 plate with the film ends, teeth 9 are provided. These teeth may be struck or bent from the top face of the metal, and are arranged in longitudinal series adjacent the lateral edges of the plate 8. The teeth are 100 spaced inwardly from the lateral edges of the plate a distance equal to the distance between the openings 7 and the lateral edges of the picture film, in order that the said teeth may project through and readily engage within the openings in the said film. The teeth also, are spaced from each other longitudinally of the plate a distance equal to that between the openings 7 in the said 105 film. As shown in the drawing, the teeth of 110

each series are arranged in transverse alignment throughout the extent of the plate. It will also be observed that the teeth of each series are inclined in opposite directions, 5 that is, the teeth adjacent the opposite ends of the plate are inclined inwardly therefrom, and it is apparent that from this construction, that when the broken ends of the film are secured over the teeth, one to each 10 extremity respectively of the plate, pull or strain upon the film ends in opposite directions will tend to securely bind the same to the base of the teeth. I preferably construct the teeth or detents 9 to provide points 15 at their free ends, and are of a width at their bases substantially equal to that of the feed openings 7 on the picture strip. This construction enables the plate to be quickly applied to the film ends, and to create at the 20 base of each tooth a relatively secure binding action.

From this description, it is apparent that when a film becomes broken during the exhibition of pictures, one of the plates may 25 be quickly applied to effect a substantially positive connection between the said film ends. The arrangement of a plurality of teeth upon the plate, while not essential, is resorted to in order to insure engagement of 30 at least one or more of the teeth with the film ends during rapid application of the device. It is also apparent that the flexibility of the plate 8 enables the same to conform readily to the curvature of the film 35 when being wound upon a reel. While the plate is by no means of such thickness or weight as to hinder the operation of the projecting mechanism, it is apparent that during the rewinding operation the same may 40 readily be observed by the operator, whereupon he may detach the plate and properly cement, or in any preferred manner secure the broken ends. It will also be observed 45 that owing to the substantially short duration of the connecting plate, the continuity

of the picture strip will not be materially impaired during the exhibition.

I claim:

1. In a device of the class described, a plate, teeth arranged on said plate adjacent the lateral edges and the ends thereof, the said teeth being alined longitudinally and laterally, and the said teeth projecting inwardly from the adjacent ends of said plate, substantially as described. 55

2. In a device of the class described, a plate, a series of teeth arranged in longitudinal alinement adjacent the lateral edges of said plate, and the teeth adjacent the ends of said plate being inclined inwardly therefrom, substantially as described. 60

3. In a device of the class described, a plate, a series of teeth arranged in longitudinal alinement adjacent each of the lateral edges of said plate, the teeth adjacent the ends of said plate being inclined inwardly therefrom, and the teeth of each series being alined transversely, substantially as described. 65

4. In a splicer for picture film, a plate 70 formed of thin flexible metal substantially the same width as the film, a series of longitudinally alined teeth formed to project from one face of the plate adjacent each of the lateral edges thereof to engage the feed 75 openings in said film, the said teeth being spaced longitudinally of the plate a distance equal to that between said feed openings, each tooth being pointed at its end and of a width at its base equal to the width of said 80 feed openings, and the teeth of each series being inclined inwardly from the adjacent ends of said plate substantially as described.

In testimony whereof, I affix my signature, in the presence of two witnesses.

JOHN THAISON.
